UNITED STATES PATENT OFFICE.

LOUIS TROST, OF CHICAGO, ILLINOIS.

DESIGN FOR A GAME TABLE.

Application filed October 23, 1924. Serial No. 11,154. Term of patent 14 years.

To all whom it may concern:

Be it known that I, LOUIS TROST, a citizen of the United States, residing at Chicago, in the county of Cook and State of Illinois, have invented a new, original, and ornamental Design for a Game Table, of which the following is a specification, reference being had to the accompanying drawing, in which a perspective view of the design is shown.

I claim:—

The ornamental design for a game table, as shown.

In testimony whereof I affix my signature.

LOUIS TROST.
